UNITED STATES PATENT OFFICE.

GULIAN V. P. LANSING, OF CHICAGO, ILLINOIS, ASSIGNOR TO AERMORE MANUFACTURING COMPANY, OF CHICAGO, ILLINOIS, A CORPORATION OF ILLINOIS.

DESIGN FOR AN AUTOMOBILE-HORN.

43,222.

Specification for Design.

Patented Nov. 5, 1912.

Application filed July 29, 1912. Serial No. 712,199. Term of patent 7 years.

To all whom it may concern:

Be it known that I, GULIAN V. P. LANSING, a citizen of the United States, residing at Chicago, in the county of Cook and State of Illinois, have invented a new, original, and ornamental Design for Automobile-Horns, of which the following is a full, clear, and exact description, reference being had to the accompanying drawings, forming a part hereof.

My design relates to warning horns or signals for use in connection with automobiles, motor-cycles and similar vehicles, to be attached to the exhaust of the engine thereof and operated by the pressure of the expelled gases, and has for its object to provide a contrivance of this character that is neat and artistic in appearance, as well as compact and convenient.

In the drawings: Figure 1 is a longitudinal elevation of my ornamental design for an automobile horn or the like. Fig. 2 is an end view thereof. Fig. 3 is an end view taken opposite to Fig. 2.

Referring to the drawings, it will be observed that my design consists of a cylind-

rical coupler or head that is open at one end and its opposite closed end is provided with a plurality of discharge openings. The reduced ends of a number of hollow tubes are secured in said closed end, said tubes being substantially right angle triangular shape in cross-section. These tubes are usually four in number and are arranged so that their apices meet and form themselves around the central axis of the horn so that their longer faces will be outermost and shape the horn into a rectangle or square. The tubes are of various lengths, and adjacent their tapered portions are each provided with an opening that has straight edges.

What I claim is:—

The ornamental design for an automobile horn, as shown and described.

In witness whereof I have hereunto set my hand and seal this 28th day of June, 1912.

GULIAN V. P. LANSING. [L.S.]
